UNITED STATES PATENT OFFICE.

LEO J. GRUBMAN, OF NEW YORK, N. Y., ASSIGNEE, BY MESNE ASSIGNMENTS, TO VOICES, INCORPORATED, OF NEWARK, NEW JERSEY, A CORPORATION OF DELAWARE.

ARTICULATIVE SOUND-PRODUCING DEVICE.

Original application filed March 11, 1922, Serial No. 542,884. Divided and this application filed December 26, 1923. Serial No. 682,675.

This invention relates to articulative sound producing devices and constitutes a division of my pending application for patent filed March 11, 1922, Serial No. 542,884.

In my original application, I have disclosed an articulative sound producing device for dolls and other toys wherein the operative parts of the mechanism are entirely enclosed within a housing or casing, said mechanism including a suitable sound producing reed and a bellows for expelling air therethrough having a gravity movable head together with a fixed axially positioned post extending between the ends of the housing or casing for supporting and guiding said bellows head. This general combination of elements is broadly claimed in said pending application. In my present divisional application I claim only a specific embodiment of the original disclosure, the primary object being to provide an axially extending guide for the movable bellows head of tubular form through which the air is expelled and within which the sound producing reed is suitably mounted so that said guide in addition to its function as a supporting and guiding means for the bellows head, serves also as a sound receiving chamber from which the sound is emitted at a point adjacent the emission apertures in one end wall of the casing in uniform volume.

It is also an object of my present invention to provide a simplified and improved mounting for the tubular guide and sound receiving chamber between the opposite ends of the casing or housing so as to enable the several parts to be expeditiously assembled in operative relation with each other.

With the above and other objects in view, the invention consists in the improved articulative sound producing device and in the form, construction and relative arrangement of the several parts as will be hereinafter more fully described, illustrated in the accompanying drawing and subsequently incorporated in the subjoined claims.

With the above and other objects in view, the invention consists in the improved articulative sound producing device and in the form, construction and relative arrangement of the several parts as will be hereinafter more fully described, illustrated in the ac-

companying drawing and subsequently incorporated in the subjoined claims.

In the drawing wherein I have illustrated one simple and practical embodiment of my present improvements and in which similar reference characters designate corresponding parts throughout the several views:

Figure 1 is a central longitudinal section illustrating one practical embodiment of the invention and showing the bellows collapsed;

Figure 2 is a similar view with the device in reversed position and the bellows expanded;

Figure 3 is a detail elevation of the tubular guide post and sound receiving chamber;

Figure 4 is a similar view of the weight member on the movable bellows head; and

Figure 5 is a detail plan view of the fixed head disc of the bellows detached from the end plate or cap of the casing.

The several operative parts of the sound producing and emitting mechanism are wholly contained and enclosed within a shell or casing 5. As herein shown this casing is of cylindrical form and the body wall thereof may consist of heavy cardboard or other suitable material. The opposite ends of this casing are closed by means of the end caps or plates 6 and 7 respectively each of which has a marginal annular flange for frictional engagement with the body wall 8 of the casing.

The end cap 6 of the casing is provided with a plurality of suitably arranged sound emission apertures 8 and centrally thereof the wall of the cap is formed with a circular depression or indentation 9 the purpose of which will presently appear.

Upon the inner side of the other closure cap 7 for the casing a disc 10 of cardboard or other suitable material is positioned, and this disc closes one end of a bellows chamber, the flexible body wall 11 of which is suitably secured at one of its end edges to the marginal edge of said disc. The other end of this flexible bellows wall is securely attached to the edge of the movable bellows head 12 to which a weight 13 is centrally fixed. This weight has an axially extending bore or opening 14 and a sound emission

slot or opening 15 extends transversely through one side of said weight and communicates at its inner end with the bore 14. This inner end of the opening 15 has its 5 longer dimension extending circumferentially of the bore 14 and is of rectangular form as clearly seen in Figure 4 of the drawings, and which feature of my construction is of primary importance in producing a 10 clear and realistic enunciation of the simulated word syllables, as will more clearly appear from the following description.

The movable bellows head 12 with its 15 weight 13 is supported and guided in its gravity movement within the casing 5 by a tubular post 16. In this particular embodiment of my invention, said post bears a fixed relation to the walls of the casing 5, and as herein shown, I preferably provide said tube at one of its open ends and at diametrically opposite points with longitudinally projecting lugs or extensions 17. To the end head or disc 10 of the bellows there is centrally secured a relatively small 25 disc of cardboard or wood 18, which is provided in its edge at diametrically opposite points with the rectangular notches or recesses 19 of such dimensions that the lugs 17 will closely fit therein. Thus it 30 will be understood that these lugs and the disc 18 effectively prevent a turning or rotative movement of the tube 16 and also tightly hold the disc 10 against the closure 7. From reference to Figure 1 of the drawing 35 it will be noted that the lugs 17 are of such length relative to the thickness of the disc 18 that the end edges of the tube wall between said lugs are spaced from the surface of said disc, thus affording openings or passages 20 through which air may 40 freely enter into the bellows chamber or be expelled therefrom into the tube 16.

The tube 16 has a close sliding fit within the bore 14 of the weight 13, while permitting of the free gravity sliding movement of 45 said weight and the bellows head. When the end cap 6 of the casing is applied, the central protuberance formed by the depression 9 in the cap wall fits within the other 50 open end of said tube as clearly shown in Figure 1 of the drawing. Thus it will be apparent that the tube is securely held in fixed relation to the casing and the movable bellows head against either rotative movement or lateral or axial displacement with 55 respect thereto, and at the same time the fixed bend or disc 10 of the bellows is frictionally clamped in concentric relation to the casing against the inner face of the end cap 7.

Within the tubular post 16 and adjacent to the openings 20, a sound producing reed 21 of any approved type is suitably mounted. As herein disclosed, I mount this disc in a 60 plug 22 of cork or other compressible ma-

terial which has tight frictional engagement with the tube wall and thus prevents leakage of air past said plug and assures maximum sound productivity in the deflation of the bellows. Adjacent to the other end of the tube 16, the wall thereof on the side corresponding with the location of the opening 15 in the weight 13 is provided with a circumferentially extending slot or opening 23 and also with the nasal orifice 23'. It is 75 to be observed that this slot likewise is of rectangular form.

In the operation of the device as above described, when the casing with the enclosed mechanism is substantially inverted 80 from the position shown in Figure 2 of the drawings, the bellows head 12 and the weight 13 move by gravity upon the wall of the tube 16 so that the air is expelled from the interior of the bellows through the 85 openings or passages 20 and the reed 21, thus producing sound. The interior of the tube 16 constitutes a receiving and collecting chamber for the sound waves, and as the rectangular inner end of the opening 15 in 90 the weight 13 passes the rectangular opening 23 in the wall of said tube, sound is emitted therefrom and through the apertures 8 in the end cap of the casing in exact volume for a predetermined length of time, 95 depending of course upon the width of the inner end of the opening 15. Initially, or before the opening 15 comes into approximately full registration with the opening 23 in the tube wall the first emission of 100 sound through the orifice 23' in the tube wall simulates the letter "m" which is immediately followed by the letter "a," thus producing a simulation of the word syllable "ma." During the passage of the solid portion of the head 13 at one side of the opening 15 past the slot 23 in the tube wall, the letter "m" will again be sounded and when 105 the weight 13 moves entirely beyond or below said slot 23 there will be a prolonged sounding of the final letter "a" thus completing the second syllable "ma." In this manner, the infant cry "ma-ma" will be realistically simulated. I have found that a distinct and clear enunciation of the two 110 syllables is primarily dependent upon the form or shape of the openings 15 and 23, and that it is essential that the emission of sound shall be initiated at all points along the edge of the slot or opening 23 as the 115 edge of the opening 15 passes the same at exactly the same instant. If there is a gradual increase in the volume of sound emitted, the letter "m" is not sharply and distinctly sounded, but the audible impression of the 120 emitted sound is more like "wa-wa." It will be understood that it is not essential that the openings 23 and 15 shall be of the exact rectangular elongated form shown in the drawings, the essential consideration be- 125 130

ing the relationship of the first meeting edges of these openings in the air expelling movement of the head 12. In other words, these meeting edges are in parallel relation with each other so that in the initial partial registration of said openings there is a uniform area through which the sound is emitted from the interior of the tube 16. Accordingly, the sounding of the letter "a" immediately following the letter "m" occurs instantaneously or abruptly and there is no merging of the sounding of one letter into the other which would produce the audible effect above referred to.

15 From the foregoing description considered in connection with the accompanying drawing, the novel subject matter of my present application will be clearly understood. Thus three essential features of the structure above described are herein claimed, namely, the sound receiving chamber in the form of a tube which guides the air expelling member in its movement, the manner of mounting and assembling this tube with relation to the bellows and the ends of the casing, and the specific form of the coacting sound emission control openings in the weight 13 and the wall of said tube. It may here again be noted that no claim is made in this application to the general or broad combination of an air expelling bellows having a gravity movable head and the fixed axially extending guide and support for said head within the casing, since such claims are embodied in my original application above identified. Nevertheless, it will be manifest that the features of construction herein emphasized might be exemplified in other structural forms than that which I have selected for the purposes of illustration, and accordingly, it is to be understood that in practice the privilege is reserved of adopting all such legitimate changes in the form, construction and relative arrangement of the several parts as may be fairly embodied within the spirit and scope of the invention as claimed.

I claim:

1. In a sound producing device, an air chamber, slidably engaged members one of which is fixed and the other movable to expel air from said chamber in its movement in one direction, a sounding reed through which the air is expelled from said chamber, one of said members being of tubular form and constituting a sound receiving chamber, and said members having coacting sound emission ports governing the emission of sound from said chamber.

60 2. In a sound producing device, an air chamber having a flexible wall fixed at one of its ends, slidably engaged members one of which is fixed to the other end of said flexible wall for movement with relation to the other member, a sound producing reed

through which air is expelled from said chamber in the movement of the latter member in one direction, one of said members being of tubular form and constituting a sound receiving chamber, and said members having coacting sound emission ports governing the emission of sound from said chamber.

3. In a sound producing device, a bellows having a movable head, a sound producing reed through which air is expelled from the bellows chamber in the movement of said head in one direction, a guide member for said head having a rectangular sound emission opening therethrough, and a part carried by said bellows head slidingly engaged upon said guide and provided with a rectangular opening therethrough to coact with the opening in the guide member and govern the emission of the sound through said opening.

4. In a sound producing device, an air chamber and a movable member expelling air from said chamber in its movement in one direction, a sound producing reed through which the air is expelled, a relatively stationary member, a part carried by said movable member slidably engaged with said stationary member, said part and the stationary member having coacting sound emission control openings, the first meeting edges of said openings in the air expelling movement of said member being parallel with each other to thereby effect an initial partial registration of said openings of uniform area for the emission of sound therethrough.

5. In a sound producing device, a casing, a bellows within said casing having a movable head, a tubular member supported between the ends of the casing and communicating at one of its ends with the bellows chamber, a sound producing reed mounted within said member, said member constituting a sound receiving chamber, and means controlled by said bellows head in its movement in one direction to govern the emission of the sound from said chamber.

6. In a sound producing device, a casing, a bellows within said casing having a movable head, a tubular member supported between the ends of the casing and communicating at one of its ends with the bellows chamber, a sound producing reed mounted within said member, said member constituting a sound receiving chamber and having a sound emission opening in the wall thereof adjacent to its opposite end, and means carried by the movable bellows head to coact with said opening and governing the emission of sound from said chamber.

7. In a sound producing device, a casing, a bellows within said casing having a movable head, a tubular member supported between the ends of the casing and communicating at one of its ends with the bellows

chamber, a sound producing reed mounted within said member, said member constituting a sound receiving chamber and having a sound emission opening in the wall thereof adjacent to its opposite end, and a weight fixed to said bellows head and mounted upon said tubular member for sliding gravity movement adapted to coact with said emission opening in the movement of the head in one direction and governing the emission of sound from said chamber.

8. In a sound producing device, a casing, a bellows within said casing having a movable head, an axially positioned tubular guiding member for said movable bellows head mounted between the ends of said casing, said tubular member at one of its ends communicating with the bellows chamber, a sound producing reed through which the air is expelled from said chamber, said tubular guiding member constituting a sound receiving chamber and being provided in the wall thereof with a sound emission opening, and means carried by the bellows head to coact with said opening in the movement of said head in one direction to govern the emission of sound from said chamber.

9. In a sound producing device, a casing, a bellows enclosed within said casing having a weighted gravity movable head, an axially positioned tubular member supported upon the casing ends, a sounding reed in communication with the interior of the tubular member and through which the air is expelled from said bellows chamber in the movement of said head in one direction, said tubular member constituting a supporting guide for said bellows head and a sound receiving chamber, and said movable bellows head and the wall of said tubular member having coacting means governing the emission of sound from said chamber in the movement of the bellows head in one direction.

10. In a sound producing device, a bellows having a movable head, a sound producing reed through which air is expelled from the bellows chamber in the movement of said head in one direction, a tubular guide for said bellows head receiving the sounds emanating from said reed and constituting a sound receiving chamber, the wall of said guide having a rectangular sound emission opening therethrough, and a part carried by the bellows head and provided with a rectangular opening to coact with the opening in the wall of said guide member and govern the emission of sound from said chamber.

11. In a sound producing device, a casing having an air chamber therein, a gravity movable air expelling member, a tubular member supported upon the casing ends and constituting a guide for said air expelling member, a sound producing reed through

which air is expelled from said chamber in the gravity movement of said expelling member in one direction, said reed communicating with the interior of said tubular guide and said guide constituting a sound receiving chamber, the wall of said guide having a sound emission opening therethrough, and means carried by said air expelling member to coact with said opening and govern the emission of sound from said receiving chamber.

12. In a sound producing device, a casing having an air chamber therein, a gravity movable air expelling member, a tubular member supported upon the casing ends and constituting a guide for said air expelling member, a sound producing reed through which air is expelled from said chamber in the gravity movement of said expelling member in one direction, said reed communicating with the interior of said tubular guide and said guide constituting a sound receiving chamber, the wall of said tubular member having a circumferentially extending rectangular emission opening through the wall thereof, and said air expelling member carrying a weight provided with a rectangular opening therethrough adapted to coact with said opening in the wall of the tubular member to govern the emission of sound from said receiving chamber.

13. In a sound producing device, a casing, a bellows contained within said casing having a gravity movable head, an axially positioned tubular guide for said head, a closure for each end of the casing, means on one of said closures engaged by means on one end of said tubular guide to prevent rotative movement of the guide, the other closure being centrally provided with means projecting into the other end of the tubular guide to hold the latter against displacement, a sound producing reed communicating with the interior of said tubular member and with the bellows chamber, said tubular member constituting a sound receiving chamber, and said bellows head and the wall of the tubular guide having coacting means governing the emission of sound from said chamber in the gravity movement of the bellows head in one direction.

14. In a sound producing device, a casing having an air chamber therein, and a gravity movable member for expelling air from said chamber, a sound producing reed through which the air is expelled, a guide for said air expelling member, and closures for the opposite ends of said casing, one of said closures having a central portion projecting from the plane of said closure and coacting with one end of said guide to retain the latter in fixed coaxial relation to said casing.

15. In a sound producing device, a casing having an air chamber therein, a sound producing reed, a member movable in said cas-

- ing to expel air from said chamber through said reed, a tubular guide for said air expelling member, said guide and the member having coacting sound emission controlling means, and closures for the opposite ends of said casing each having means coacting with the respective ends of said guide to retain the latter in fixed coaxial relation to said casing, said means on one of the closures consisting of a centrally projecting boss engaged by one end edge of said tubular guide whereby said end of the guide is held against lateral displacement from its assembled position.
15. 16. In a sound producing device, an air chamber, a post extending through said air chamber and provided with sound emission means, an air expelling member in said chamber having an opening therein through which said post extends and said opening receiving the sound emission means of said post in the longitudinal sliding movement of the member along said post, a sounding reed through which the air is expelled, and
- said member having means coacting with 25 said sound emission means to effect an articulated emission of the sound in the movement of the air expelling member in one direction.
17. In a sound producing device, a bellows having a movable head, a sounding reed 30 through which air is expelled from the chamber in the movement of said head in one direction, a stationary post extending through the bellows chamber and the movable head thereof and upon which said bellows head is slidably supported and guided, said post being provided in a part of its structure with sound emitting passages over which said bellows head has free sliding movement, said bellows head being provided with means 35 coacting with said sound emitting passages of the post to effect an articulated emission of the sound in the air expelling movement of the bellows head in one direction.

In testimony that I claim the foregoing 45 as my invention, I have signed my name hereto.

LEO J. GRUBMAN.
